E. B. GIBFORD.
COMBINATION RAZOR HONE AND STROP.
APPLICATION FILED JUNE 29, 1917.

Patented Feb. 19, 1918.

UNITED STATES PATENT OFFICE.

EDWARD BACON GIBFORD, OF ADRIAN, MICHIGAN, ASSIGNOR TO PIKE MANUFACTURING CO., OF PIKE, NEW HAMPSHIRE, A CORPORATION OF NEW HAMPSHIRE.

COMBINATION RAZOR HONE AND STROP.

1,257,078.

Specification of Letters Patent. Patented Feb. 19, 1918.

Application filed June 29, 1917. Serial No. 177,649.

To all whom it may concern:

Be it known that I, EDWARD BACON GIBFORD, a citizen of the United States, residing at Adrian, in the county of Lenawee, State 5 of Michigan, have invented certain new and useful Improvements in Combination Razor Hones and Strops, of which the following is a description, reference being had to the accompanying drawings, forming a part 10 hereof.

My invention relates to razor strops and has for its object to provide a razor strop which will be adapted to fold up when not in use so as to be readily carried in a traveling bag or soldier's kit, will carry a hone and will have a pocket for a razor.

With these and other objects hereinafter explained in view my invention consists in the construction and combination of elements hereinafter described and claimed.

Referring to the drawings:

Figure 1 is a perspective view of a razor strop embodying my invention shown open.

Fig. 2 is a perspective view of the strop 25 closed and

Fig. 3 is a side view partly in central longitudinal section, of the strop as shown in Fig. 2.

The strop as shown in the drawings is 30 made up of an inner layer 1 and an outer layer 2 of leather or other flexible material of which the inner layer, at least, is adapted for stropping a razor. The strop has at one end a handle 3 and at the other end is folded 35 over as shown at 4 to hold a loop 5 of cord or the like. Midway between its ends recesses 6 are formed in opposite sides so that the strop will readily bend or fold in line with these recesses.

The two layers 1 and 2 are preferably 40 cemented together from the handle end to a point beyond the recesses 6 and from this point to the loop end are held together by lines of stitching 8 along the edges and cross 45 lines 9 and 10 near the loop end respectively the line of stitching 10 serving to hold the infolded end 4.

Near the loop end the outer layer 2 is cut 50 to form a tongue 11 the opening formed by the cut serving as the entrance to the space between the layers 1 and 2 which forms a pocket to receive a razor. The tongue 11 is provided with one member 12 of a separable 55 spring fastener and the handle 3 is provided

with the other member 13 of the fastener the 55 handle being adapted when the strop is closed to extend through the loop 5 and to have its fastener member come into engagement with the fastener member on the tongue thus holding the tongue closed and 60 also holding the strop in folded position. The fastener member 13 on the handle is preferably the socket member and being secured in place in the usual manner serves to aid in holding the two layers 1 and 2 to 65 together.

On the portions of the strop between the recesses 6 and the loop 5, near the ends of this portion I provide cross strips 14 and 15 having respectively short tongue portions 16 70 and 17 extending toward each other and each provided with one member of a separable spring fastener 18. The cross strips 14 and 15 are conveniently secured in position by the lines of stitching 8. The tongues 16 75 and 17 are adapted to receive beneath them the ends of a flat plate 20 preferably of metal carrying a hone 29 and having on its ends fastener members 22 adapted to be engaged by the fastener members 18 on 80 tongues 16 and 17. By separating these fasteners the plate 20 carrying the hone may be readily removed.

The plate 20 lies flat against the inner layer 1 of the strop, when in position and 85 prevents any bending of this portion of the strop thus protecting the razor 23 in the pocket.

The plate 20 may be provided with a mirror in place of the hone or in place of a part 90 of the hone.

The loop 5 serves as a convenient means for carrying the device in folded condition and when the device is to be used for sharpening a razor this loop may be slipped over 95 any convenient hook or even slipped over the toe of the user's boot.

It will of course be understood that I do not desire to be limited to the particular construction shown and described or to the use 100 of any particular material.

Having thus described my invention what I claim is:

1. A combination razor strop and hone comprising a strip of flexible material weakened between its ends to permit the two portions thereof to fold together one on the other, one portion being on one face adapted

to serve as a strop and the other portion being provided on its corresponding face with a removable hone.

2. A combination razor strop and hone comprising a strip of flexible material weakened between its ends to permit the two portions thereof to fold together one on the other, one portion being on one face adapted to serve as a strop and the other portion being provided on its corresponding face with a removable hone, the hone carrying portion being provided with a pocket having the opening leading thereto on the face opposite to that on which the hone is carried, a tongue closing the pocket opening having a fastener member thereon and an extension on the outer end of the strop portion adapted to fold over the outer end of the hone carrying portion and having a fastener member adapted to engage the fastener member on the tongue of the hone carrying member. 45
5. A combination razor strop and hone comprising a strip formed of two layers of flexible material having their flat sides secured together through part of their length, and weakened between its ends to permit the 50 two portions thereof to fold together one on the other, the one portion being on one face adapted to serve as a strop and the other portion carrying on its corresponding face a hone, the layers of the hone carrying portion being secured together at their edges only so as to form between them a pocket open at one end. 55
4. A combination razor strop and hone comprising a strip of flexible material weakened between its ends to permit the two por-

tions thereof to fold together one on the other, one portion being on one face adapted to serve as a strop and the other portion being provided on its corresponding face with a removable hone, the hone carrying portion being provided with a pocket having the opening leading thereto on the face opposite to that on which the hone is carried, a tongue closing the pocket opening having a fastener member thereon and an extension on the outer end of the strop portion adapted to fold over the outer end of the hone carrying portion and having a fastener member adapted to engage the fastener member on the tongue of the hone carrying member. 45

5. A combination razor strop and hone comprising a strip of flexible material adapted to be bent between its ends to divide it into two portions, one portion being on one face adapted to serve as a strop and the other portion being provided on its corresponding face near its end with cross strips each carrying a fastener member and a plate of relatively stiff material carrying a hone and provided at its ends with fastener members adapted to engage the fastener members of the cross strips. 55

In testimony whereof I affix my signature this 22d day of June, 1917.

EDWARD BACON GIBFORD.
